GRINDING ATTACHMENT FOR LATHES

Roy A. Schramm, Bay City, Mich., assignor of forty per cent to Earl S. Johnson, Bay City, Mich.

Application March 13, 1944, Serial No. 526,145

6 Claims. (Cl. 51—259)

This invention relates to grinding attachments for surface grinding and more specifically to an attachment for use in connection with conventional lathes.

One of the prime objects of the invention is to provide an economical and practical grinding attachment for mounting on a conventional lathe, eliminating the necessity of the shop owner purchasing an individual grinder with drive with fittings, thus making possible the accomplishment of lathe work and surface grinding with a minimum investment in equipment, conserving floor space, and also providing an attachment from which the grinding wheel and drive can be removed as a unit for hand grinding operations when desired.

Another object is to provide an attachment which can be quickly and easily mounted on the bed plate of the lathe so that the work may be reciprocated by the lathe, and the cross slide operated in the conventional manner for evenly and accurately grinding the work.

A further object still is to provide a grinding attachment including means for vertically and longitudinally adjusting the grinding member with relation to the work as well as a scale for facilitating the setting of the tool.

Still a further object is to provide a simple and substantial supporting frame which can be easily mounted and/or removed from the lathe bed.

A still further object is to provide a grinding attachment which is readily adjustable to the conventional lathe at present in general use as well as to new lathes in the process of manufacture.

With the above and other objects in view, the present invention consists in the combination and arrangement of parts, hereinafter more fully described, illustrated in the accompanying drawing and more particularly pointed out in the appended claims, it being understood that changes may be made in the form, size, proportion, and minor details of construction, without departing from the spirit, or sacrificing any of the advantages of the invention.

In the drawing:

Fig. 1 is a front elevational view of the conventional lathe showing my grinding attachment in place thereon;

Fig. 2 is an end elevational view of the grinding attachment taken on the line 2—2 of Fig. 1;

Fig. 3 is an end elevational view of the bracket support; and

Fig. 4 is a fragmentary front elevational view showing a modified construction.

- Referring now more particularly to the drawing in which I have shown the preferred embodiment of my invention, the letter "B" indicates a structural, preferably welded, bracket support 5 on which the attachment is mounted, this comprises a horizontally disposed guide bar 7 terminating in end members 8 having base sections 9 as shown, and angularly disposed brace members 10 are welded in position to reinforce the structure. A bar 11 is inserted beneath the ways 12 of the lathe bed "L," and openings 13 are provided in the members 9 and 11 respectively to accommodate bolts 14 to rigidly clamp the base to the lathe bed.
- 15 The grinding attachment proper is mounted on the guide bar 7 and comprises a bracket 15 suitably grooved as at 16 to slidably accommodate the guide bar, and a face plate 17 fits over said groove and is held in position by means of set screws 18 in the usual manner.
- 20 Vertically disposed guide rods 19 are slidably mounted in the bracket 15 and a split bearing 20 is provided on the lower end thereof, said bearing being secured in assembled relation by means of bolts 21 or the like.
- 25 An internally threaded opening 22 is provided in the bracket 15 between the guide rods 19, and a threaded screw member 23 is threaded therethrough, with the lower end revolvably secured to the bearing 20, the upper end extending 30 through the cross member 24 which secures the upper ends of the guide rods together.
- 35 A hand wheel 25 is provided on the upper end of the screw 23 and a handle 26 projects therefrom to provide for easy manipulation of the wheel, the lower hub section of the wheel being suitably graduated as at 27, and an indicator 28 is mounted on the member 24 to facilitate the setting of the tool.
- 40 A horizontally disposed shaft 29 is mounted in the bearing 20, and a grinding wheel 30 is secured thereon in the conventional manner, a hooded section 31 forming a cover for the grinding wheel, and can be formed integral with or bolted to the bearing 15 as desired.
- 45 The shaft 29 is suitably connected to the drive shaft of the motor 33, this motor being of conventional design, and connecting wires 34 lead to a suitable source of electric current supply.
- 50 The attachment is longitudinally adjustable on the bar 7 and is held in adjusted position by means of a set screw 35 which is threaded in the bracket 15, and it will be obvious that manipulation of the hand wheel 25 will raise or lower the 55 grinding wheel as desired.

The "work" to be ground (not shown), is clamped on the table 36 which is fitted on the lathe cross slide 37, this slide is a part of the lathe and is manipulated in exactly the same manner as at present, so that the "work" is handled in the conventional manner.

To eliminate any possibility of slippage or change in adjustment after the device has been set, I provide a set screw 40 as shown, this is provided with a soft end for engagement with the threaded screw 23 to hold it in position.

In Fig. 4 of the drawing I have shown a slightly modified construction, the only difference being that a motor 38 is adjustably mounted on the guide bar 7 and a sheave (not shown) is provided on the shaft 29, a belt 39 serving to drivingly connect said motor and the drive shaft 29 on which the grinding wheel 30 is mounted.

The grinding wheel and motor are readily removable as a unit, so that it can be used as a hand grinding tool when desired, it being merely necessary to unscrew the bolts 21 and the motor and grinding wheel will be free.

From the foregoing description it will be obvious that I have perfected a very simple, practical and economical hand grinding attachment for lathes which can also be used as a hand tool when desired.

What I claim is:

1. A grinding attachment for lathes comprising, spaced apart end frames detachably secured to the face of a lathe bed, a rigid guide bar connecting the upper ends of the end frames a bracket mounted on the guide bar and adjustable longitudinally thereon, a grinding wheel assembly mounted on said bracket, and means for vertically adjusting said wheel assembly.

2. A surface grinding attachment for lathes comprising, spaced apart end frames detachably secured to the lathe bed a horizontally disposed guide bar, rigidly connecting the upper ends of said end frames a bracket mounted on said bar and longitudinally adjustable thereon, vertically adjustable guides slidably mounted in said bracket, a bearing on the lower end of the guides, a shaft journaled therein, a grinding wheel on the shaft, and a motor drivingly connected to said shaft.

3. A grinding attachment for lathes comprising, spaced apart end frames adapted to be rigidly and detachably secured to a lathe bed, a horizontally disposed guide bar connecting the upper ends of said frames, a bracket mounted for longitudinal adjustment on said bar, vertical guide rods slidably mounted in said bracket, a split bearing secured to the lower end of said rods,

a grinding wheel shaft journaled in said bearing, an abrasive wheel mounted on said shaft, and an individual driving unit connected direct to said shaft so that the grinding wheel, shaft, and drive member can be disconnected as a unit.

4. A grinding attachment for lathes comprising, a rigid bracket support securely and detachably mounted on the lathe bed, said support including spaced apart substantially V-shaped end frames with a guide bar connecting the upper ends of said end frames, a bracket mounted on the guide bar and adjustable longitudinally thereon, vertically adjustable means slidably mounted in said bracket and having a bearing on the lower end thereof, a grinding wheel shaft journaled therein, a grinding wheel mounted on the shaft, and a threaded adjusting member mounted in said bracket and operable to vertically adjust said grinding wheel with relation to the lathe bed.

5. A grinding attachment for lathes comprising, a rigid bracket support securely mounted on the lathe bed, and comprising spaced apart end frames with a guide bar rigidly connecting said end frames, a bracket mounted on the guide bar and adjustable longitudinally thereon, vertically adjustable guide bars slidably mounted in said bracket and provided with a bearing on the lower end thereof, a removable grinding wheel assembly journaled in said bearing, a threaded adjusting member mounted in said bracket for vertically adjusting said assembly, a hand wheel on said threaded member, graduations on the hub thereof, and means for securing said adjusting member in adjusted position.

6. The combination with a lathe, of a table mounted on the cross slide of the lathe and on which the "work" is mounted, a rigid bracket support mounted on the lathe bed and comprising spaced apart end frames spanning said table, and a guide bar rigidly connecting said end frames, a bar beneath the lathe bed, securing means engageable with said frame and bar for securing the frames to said lathe bed, a bracket mounted on the guide bar and adjustable longitudinally thereon, vertically adjustable means slidably mounted in said bracket and provided with a bearing on the lower end thereof, a removable grinding wheel assembly journaled in said bearing, a threaded adjusting member mounted in said bracket for vertically adjusting said assembly and grinding wheel towards and away from said table, a hand wheel on said threaded member, graduations on the hub thereof, and means for securing said adjusting member in adjusted position.

ROY A. SCHRAMM.
